UNITED STATES PATENT OFFICE.

GEORGE W. BOBLIT, OF BALTIMORE, MARYLAND.

ENVELOP-FASTENER.

1,123,983.

Specification of Letters Patent.

Patented Jan. 5, 1915.

Application filed June 17, 1914. Serial No. 845,659.

To all whom it may concern:

Be it known that I, GEORGE W. BOBLIT, a citizen of the United States, residing at Baltimore, in the State of Maryland, have invented certain new and useful Improvements in Envelop-Fasteners, of which the following is a specification.

My invention relates to new and useful improvements in means for fastening envelopes and more particularly to metallic fastening means for sealing the flap to the body portion thereof.

The primary object of my invention is to provide an envelop fastener of the character described for securely fastening or sealing the envelop so that it cannot be opened and its contents tampered with without cutting the envelop and without mutilating the seal to such an extent that the fact of such tampering will be indicated.

Another important object is to provide a fastener of the character described that is of an extremely simple construction, is reliable and efficient in operation and inexpensive to manufacture.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a view in elevation of an envelop showing my improved fastener applied thereto, Fig. 2 is a vertical sectional view taken transversely through Fig. 1 on line 2—2 thereof, Fig. 3 is a transverse sectional view taken on line 3—3 of Fig. 2, Fig. 4 is a detail plan view of the tongue carried locking element, Fig. 5 is a plan view of the blank of which the body carried fastening element is formed, and Fig. 6 is a transverse sectional view taken through the body carried fastening element showing the sealing flap carried element inserted therein and in front elevation or top plan.

Referring to the drawings by characters of reference, the numeral 1 designates as an entirety an envelop of the ordinary construction, provided with the ordinary sealing flap 2.

Secured upon the outer face of the sealing

flap adjacent to the apex portion thereof is the sealing flap carried fastening element designated 3 as an entirety that consists of a circular body portion 4 upon opposite 69 sides of which are formed locking tongues 5 and 6 that are formed integral with the body, arranged in pairs and pointed so as to be readily inserted through the flap and bent over as clearly shown in Fig. 2. The 65 body portion 4 is provided centrally with a protuberance or raised circular portion 7 to provide a gripping surface. Formed integrally with the body portion 4 and extending outwardly therefrom between the pair 70 of tongues 6 is a locking tongue 8 that is rounded at its outer end and adjacent to said rounded end provided with an opening or slot 9 which is centrally of the longitudinal edges of the tongue and for a purpose to 75 be later more fully described. The sealing flap carried fastening member 3 is secured upon the flap in such manner that the tongue portion is extended beyond the flap in position to be engaged by the body carried locking member 3^a to be later more 80 fully described. The prongs 5 and 6 serve to securely hold the member 3^a to the flap 2.

Carried on the outer face of the body portion of the envelop at a point so that it may 85 coöperate with the member 3^a is a body carried fastening member designated 10 as an entirety that consists of a rectangular base plate 11. Longitudinally and right angularly extending flanges 12 are formed on the 90 longitudinal edges of the body plate 11 and are in turn provided at their free longitudinal edges with inwardly and right angularly extending flanges 13. It will thus be seen that a casing structure is provided 95 through the medium of the plate 11 and flanges 12 and 13 to receive the tongue 8 carried by the flap member 3. Formed integrally with the lower edge of the body plate 11 is a reduced tongue 14 that is bent 100 back so as to be disposed in spaced parallel relation to the body plate 11. The tongue 14 is pointed at its end and longer than the body plate 11. The pointed free end of the tongue 14 is inserted through the body portion of the envelop and bent over to lie upon the inner face of the body as at 105 15 and as clearly shown in Fig. 2 in the drawings.

Securing prongs 16 are formed on the 110 lower edges of the envelop body portion 11 and are inserted through the body and bent

over as at 17 to secure the member 3 securely to the envelop. A depression 18 is formed in the central part of the body portion 11 and is for a purpose as will be later more 5 fully described. The tongue 14 is cut away as at 19 substantially equi-distant of its ends.

To lock the fastener the locking tongue 8 is inserted through the space between the 10 body plate 11 and tongue 14 and the tongue 20 is inserted through the opening 9 in the free end of the tongue 8 to hold the tongue 8 against withdrawal relative to the body plate 11 and tongue 14. The depression 15 18 formed in the body plate 11 allows for the angular disposition of the bent end of the tongue 20 and the insertion thereof through the opening 9. The flap carried member 3 may be secured to the flap as described prior to the locking action above set out. After the tongue 8 has been locked as 20 described the tongue 14 is bent over as at 15 after being inserted through the envelop and the prong 16 also inserted through and 25 bent over as at 17. This securely attaches the body carried element. The flanges 12 and 13 on the body plate 11 securely hold the tongue 8 in position and act as guides when inserting the tongue. It will be readily seen that to open an envelop sealed with 30 my improved fastening means it is necessary to cut or mutilate the envelop to such extent that the fact that someone has made surreptitious attempts to gain access to the 35 interior of the envelop will be indicated.

In practice, I have found that the form of my invention, illustrated in the drawings and referred to in the above description, as the preferred embodiment, is the most efficient and practical; yet realizing that the 40 conditions concurrent with the adoption of my device will necessarily vary, I desire to emphasize the fact that various minor

changes in details of construction, proportion and arrangement of parts may be re- 45 sorted to, when required, without sacrificing any of the advantages of my invention, as set forth.

What is claimed is:—

An envelop fastener comprising two members, one carried by the sealing flap of an envelop and the other carried by the body portion of an envelop, said flap carried member consisting of a body having bendable pointed securing prongs thereon, a 55 tongue formed integral with the body and extending therefrom to coöperate with the body carried member, said tongue having an opening adjacent to its free end, the body carried member consisting of a plate, a 60 tongue formed on the lower end of the plate and being bent back in spaced parallel relation to the plate, an angularly disposed tongue formed intermediate the ends of said last named tongue, said first named tongue 65 adapted to extend between the body plate, and second named tongue, said last named tongue adapted to extend through the opening in the first named tongue, bendable prongs carried by the lower end of the body 70 plate adapted to be inserted through the body of the envelop and bent into secured position, said second named tongue being pointed and inserted through the body of the envelop and being bent to engage the 75 inner face of the body, guide flanges carried by the body portion on the sides thereof, and a depression formed in the inner face of said body plate to receive the last named tongue.

In testimony whereof I affix my signature in presence of two witnesses.

GEORGE W. BOBLIT.
